UNITED STATES PATENT OFFICE.

NAPOLEON E. GAGNON, OF WOODLAND, WASHINGTON.

CAR-STAKE.

No. 899,394.

Specification of Letters Patent.

Patented Sept. 22, 1908.

Application filed April 14, 1908. Serial No. 426,997.

To all whom it may concern:

Be it known that I, NAPOLEON E. GAGNON, a citizen of the United States, and a resident of Woodland, in the county of 5 Clarke and State of Washington, have invented certain new and useful Improvements in Car-Stakes, of which the following is a specification.

This invention is an improvement in car stakes, especially in that class of stakes for application at each side of flat cars designed to be loaded with logs, and the improved stake can be applied to the sockets generally found at the side of such cars, or can be 10 fastened thereto in various ways as will be more fully described.

In the drawings, Figure 1 is a perspective view of the stake embodying my invention applied for use. Fig. 2 is a side elevation of 20 the stake applied for use, a portion of the car being shown in section. Fig. 3 is a sectional side elevation of the improvement as in use, dotted lines being employed to indicate the released position of the stake; and Fig. 4 is a 25 face view from the outer side of the stake.

In carrying out the invention the stake comprises an upright A, and a base B, which latter may be secured to the car in any suitable way and is shown as grooved in its outer 30 face and side edges for the reception of cross bars C, and side bars C² of clips C.

The base B is provided at its upper end with the knuckles B' which receive between them the knuckle A' projecting outwardly 35 from the lower end of the upright A, and these knuckles A' and B' are connected by the pintle D on which the upright A hinges.

At the point between the pintle D and its inner edge the base B is provided with transverse openings B² in its side wings B³, and these openings B² align with an opening A² through the upright when the latter is in 40 position for use as shown in Figs. 1 to 4; and a key E is driven through the openings 45 tapering toward its end E', which is perforated to receive the hook F which operates as a keeper to prevent the accidental displacement of the key E when the latter has been driven home. A chain E² may be connected 50 with the key E, and a chain F² connected with the keeper F in order to prevent said parts from being lost.

The construction is simple, permits the upright of the stake to be turned to the position 55 for use and can be maintained in such position with a minimum strain upon its pivot or

hinge, so the key C locking the upright in position for use is located out of the way and between the hinge or pivot of the upright and the point of application of the strain to 60 the stake.

It will be understood in operation the uprights project above the bed of the car, and when it is desired to unload the car the pin or key E can be knocked out with a hammer or 65 mallet and the stake will then bend over the hinge so that the logs can roll off the side of the car.

I claim—

1. The improvement in stakes herein described, comprising a base provided at its upper end with outwardly projecting knuckles having an opening for the pintle and having side wings provided between said pintle opening and their inner edges with openings 70 for the key, an upright fitting at its lower end between the said wings and the base, and having at such end an outwardly projecting knuckle having an opening alined with the pintle openings in the knuckle of the base, the 75 said upright being also provided between its pintle and its inner edge with a key opening alined with those in the side wings of the base, the pintle and the key passed through their respective openings, and a retaining means 80 for the key, substantially as set forth.

2. A car stake comprising a base having a knuckle provided with a pintle opening, and also having between said pintle opening and the inner edge of the base a key opening, an 90 upright pivoted to the base and provided between its said pivot and its inner edge with an opening alined with the key opening in the base, and a key passed through the opening in the base and upright, substantially as 95 set forth.

3. The combination in a car stake of a base having its outer face and sides grooved for reception of a clip fitting in the grooves of the base, an upright pivoted adjacent to 100 the outer edges of its lower end to the base, the said base and the upright being provided between the said pivot and their inner edges with alined openings, and a key passed through said openings for securing the upright stake in position for use, all substantially as and for the purposes set forth.

NAPOLEON E. GAGNON.
